PRODUCTION OF FUEL OILS AND
NAPHTHENIC ACID SOAPSCyril R. Turner, Lafayette, Calif., assignor, by
mesne assignments, to California Research
Corporation, San Francisco, Calif., a corpora-
tion of Delaware

Application November 29, 1949, Serial No. 129,938

3 Claims. (Cl. 260—514)

1

This invention relates to a process of producing naphthenic acids and petroleum hydrocarbons, or, more particularly, to an improved method of producing naphthenic acids in the form of naphthenic soap and naphthenic-soap-free hydrocarbons from naphthenic-soap-containing petroleum hydrocarbon fractions.

Various crude oils are known to contain minor amounts of naphthenic acids. In order to recover naphthenic acids, it is a common practice to wash the crude oils or petroleum fractions where the naphthenic acids concentrate with an aqueous caustic soda solution in order to separate naphthenic acids in the form of soap from the hydrocarbons. Thereafter, the soap which is soluble in the aqueous caustic solution is separated from the hydrocarbons and this caustic solution may be acidified to recover the soaps in the form of naphthenic acids. The recovery of naphthenic acids has become more and more important as new uses for the acids and their salts have been found.

Naphthenic acids and their salts are used in preparing drying oil compositions for paints, detergents, and for making various fungicidal compositions, etc. The caustic washing of the crude oil or petroleum fractions converts the naphthenic acids to naphthenic soaps and extracts substantially all of the acid from the petroleum hydrocarbons. However, the known processes do not remove all of the naphthenic soaps from the oil. Though the amount of naphthenic soaps remaining in the crude petroleum or petroleum fractions after the caustic treatment do not have harmful effects in many of the applications to which the petroleum products are put, these minor amounts of soap have been found to be especially undesirable when the products are used as fuels. This is particularly noticeable when the caustic-treated gas oils are used in diesel fuels. It has been found that the small amounts of soap in diesel fuel oils result in injector plugging and filter plugging, etc. Likewise, when the gas oils are used as fuels for domestic burners, plugging of the fuel lines often occurs. In order to overcome this difficulty, many refiners have established a maximum soap content in their specifications for diesel and burner fuels. The caustic-treated petroleum fractions are commonly washed with dilute sulfuric acid to remove or destroy

2

soap in order to meet the specifications. The acid-treating process has been found to be very expensive because of the high maintenance and special handling cost.

5 It is an object of this invention to provide a method of recovering naphthenic acids in the form of soap and naphthenic-soap free hydrocarbons from petroleum hydrocarbons.

It is another object of this invention to provide 10 a method of economically recovering naphthenic acids in the form of soap and separating minor amounts of naphthenic soaps from caustic-treated petroleum hydrocarbons.

It is still another object of this invention to provide 15 a method of obtaining an alkali-treated petroleum hydrocarbon free of naphthenic soaps.

It is a further object to recover naphthenic acids in the form of soap from naphthenic-acid containing petroleum hydrocarbons and to produce 20 naphthenic-soap free petroleum hydrocarbons.

These and still further objects of the present invention will be apparent from the following description.

25 It has been discovered that fuel oils and naphthenic acids in a form of soap can be produced from naphthenic-acid containing petroleum fractions by a process comprising treating the hydrocarbons with an aqueous alkali solution which converts the naphthenic acids to naphthenic soaps, separating an aqueous alkali phase containing substantially all of the soap from the hydrocarbon phase, treating the hydrocarbon phase with an aqueous solution of a non-cationic water-soluble, surface-active agent, and separating an 30 aqueous phase containing said soap from a hydrocarbon phase free of said soap.

As used herein and in the appended claims, 35 the term "soap number" is used to express the amount of naphthenic soap present in the hydrocarbons. This term represents the number of milligrams of potassium hydroxide per gram of sample equivalent to the naphthenic soaps in the petroleum. A measured amount of acid is agitated with a measured amount of hydrocarbons and the mixture is titrated with a potassium hydroxide solution to the methyl-orange end point. The soap number is calculated in the following manner:

$$\frac{(\text{Ml. acid} \times \text{normality} - \text{Ml. KOH} \times \text{normality (for back titration)} \times \text{mol. wt. of KOH})}{\text{Ml. of sample} \times \text{specific gravity of sample}}$$

When nitrogen bases are present in the hydrocarbons being analyzed, the amount of nitrogen bases must be determined and subtracted from the above soap determination in order to ascertain accurately the amount of soap present.

In order to describe the invention in more detail, reference will now be made to the appended schematic flow diagram.

Referring to the appended diagram in which suitable apparatus is shown for practicing the process of this invention, a gas oil boiling in the range of 375-685° F. and having a naphthenic-acid content of 1.5 weight per cent held in storage tank 1 is withdrawn through line 2 and passes into pump 3 which forces the oil through line 4 into washer 1.

An 8° Baumé caustic solution held in caustic storage 5 is withdrawn through line 6 and passes into washer 7. Caustic or other alkali solutions from 1 to about 10° Baumé may be used and the amount of solution, however, depends upon the quantity of naphthenic acids present in the oil. The caustic solution or oil-caustic mixture passes out of line 8 into pump 9 which forces the caustic solution or caustic-oil mixture into line 4 through line 10. This mixture passes through a mixing zone 11 where the caustic and feed oil are mixed. A pump 9 is not always necessary to obtain the circulation of the caustic. In many instances a venturi may be employed. The mixing zone 11 may comprise a baffled line or other suitable mixing devices. Feed oil is withdrawn from storage tank 1 until the free caustic present in the washer 7 is in the range of about 4 to 10 pounds per 100 gallons of oil.

The addition of caustic solution to the naphthenic acid containing feed oil converts the naphthenic acids to sodium naphthenates which separates along with the aqueous caustic solution from the hydrocarbons in a phase separation and passes out through line 13 into product tank 14. The sodium naphthenate or naphthenate soap, as it is called, thereafter is generally separated from the free caustic and water.

Treated oil passes out line 12 into settler and surge tank 15. Entrained aqueous caustic solution and naphthenic soaps settle and pass out line 16 into line 13 and then into product tank 14.

The oil from settler 15 passes out line 17 and then into pump 18 which forces the oil through line 17. The oil in line 17 was found to have a soap content of 0.031 soap number.

Fresh water in line 20 passes into hot well 21 which is directly heated by steam from line 22. The well 21 may be heated by any suitable means. An alkyl aromatic sulfonate, a surface-active agent, having an average molecular weight of about 350 is added at a rate of about 0.00042 pound per gallon of water to hot well 21 through line 23. The aqueous sulfonate solution is pumped out of hot well 21 through line 24 by pump 10 which forces the solution through line 26. A portion of the aqueous sulfonate solution passes from line 26 through valved line 21, wherein valve 28 controls the rate of flow, into washer tower 29. Another portion of this solution passes through valved line 30, wherein valve line 31 controls the rate of flow of the sulfonate solution, into line 19. The amount or volume ratio of sulfonate solution to feed stock may vary considerably. It was found that ratios of feed stock to the surface-active solution may vary from about 1:1 to 20:1 with a ratio of about 10:1 being the most desirable. The volume ratio is somewhat dependent upon the intimacy of contact

desired, the amount of soap present in the feed, and the amount of surface-active agent in the surface-active solution.

The mixture of surface-active solution and feed passes through heater 32 where the mixture is heated. It is not always necessary to heat the water previous to the mixing nor to heat the mixture of surface-active solution and feed. In any event, it is not always necessary to use two heating means to insure adequate heating of the feed and surface-active solution. Heating generally lowers the viscosity of the feed oil so that better mixing of the surface-active agent and feed and better separation of the oil and aqueous phases can be obtained. Therefore, when the feed to be treated has a sufficiently low viscosity heating may not be necessary. However, when a brightening step is to be included in the process, the resulting mixture of aqueous surface-active solution and feed oil is generally heated to about 100 to 160° F. at this point, with 125-150° F. being preferred.

The heated mixture in line 19 passes from heater 32 into a mixing zone 33. This mixing zone may comprise a baffled line or other suitable mixing devices. The mixed feed and surface-active solution pass into washer tower 29.

The washer tower 29 may be a packed or unpacked tower or column. The tower packing may be any suitable material such as rock or various other materials or it may be a trayed tower or column.

The oil and aqueous surface-active solutions are separated by phase separation in washer 29 and the aqueous phase containing naphthenic soaps passes out line 35. A stream of aqueous surface-active solution from line 27 which passes to washer 29 near the top is added to the washer to prevent entrained surface-active solution containing the naphthenic soaps from passing overhead from washing 29. This stream is not always necessary and, in many instances, it may be preferable to use plain water instead of a surface-active solution. The treated oil phase passes out from washer 29 through line 36 into settler 39 through line 38 or into line 37. The oil passes into line 38 after valves 41 and 42 are opened and valve 40 is closed. The feed oil passes into line 37 when valve 40 is opened and valves 41 and 42 are closed when the settling step is not necessary. The settling step is used to separate or settle out minor amounts of aqueous phase from the washed oil. When valve 40 is closed and valves 41 and 42 are open, the oil passes into settler 39 wherein a further phase separation of water and oil occurs. The separated water phase containing naphthenic soap in settler 39 passes out of the bottom through line 43 and the treated oil passes out near the top through line 44. Lines 37 and 44 connect to from line 45 wherein oil from settler 39 or oil directly from washer 29 passes through heater 46 where it is heated to about 160° F. The oil in this step is generally heated within about 10° F. of the flash point of the oil in order to obtain the maximum efficiency in the brightening step. Therefore, depending on the oil being treated, different amounts of heat are added at this point. Heated oil from heater 46 passes through line 47 into brightener 48.

Air, compressed to about 30 p. s. i. passes into brightener tower or column 48 through line 49. The air needs to be compressed only to a pressure sufficient to insure an adequate flow of air through brightener 48 and it may be pre-heated

if desired. Brightener 48 may be a packed or unpacked tower, that is, similar to washer 29. The air passes upwards through the downcoming oil in brightener 48, stripping water vapor and light hydrocarbons from the oil. This step is commonly called a brightening step as minor amounts of water which may cause the oil to appear cloudy are removed. The brightening step is not always necessary when adequate separation is obtained in previous steps or when the small amount of water will not substantially effect the properties of the oil. The stripped or bright oil passes out line 51 into product storage tank 52. The stripping air containing water, vapor and light hydrocarbons passes out of the brightener 48 through line 50.

A soap-number determination conducted on the oil in tank 52 gave a soap number of 0.003.

The term "non-cationic" used in the specification and appended claims is intended to include the water-soluble surface-active agents wherein the surface-active component is either anionic or non-ionic. These surface-active agents or compounds are generally characterized by hydrophobic and hydrophilic groups. The hydrophobic group usually is an organic radical of about 8 to 20 carbon atoms. Polarity and the balance of water-oil affinities and solubilities are imparted by the hydrophobic or by a hydrophilic group. In the anionic surface-active agents the hydrophilic group is an acid or an acid-forming radical attached to the hydrophobic group and is usually utilized in the form of a salt. The non-ionic water-soluble surface-active agents are characterized by a surface-active component which does not ionize. Nevertheless, the non-ionic surface-active agents contain hydrophobic and hydrophilic groups to impart the requisite solubility and surface activity.

The non-ionic, water-soluble surface-active agents which may be used in this invention include polyglycol ethers of the following materials: alkyl phenols, fatty acid glycerides, fatty alcohols, oxo alcohols, sorbitol, mannitol, etc.; polyglycol esters of fatty acids; polyglycol esters of alkyl succinic acids; polyglycol derivatives of alkyl amines; analogs of the above prepared with propylene oxide; and alkyl polyalkylene-polyamines, etc.

The anionic, water-soluble, surface-active agents which may be used in this invention include the following groups: carboxylic acids and salts, alkane sulfonic acids and salts, alkyl aromatic sulfonic acids and salts, and sulfuric esters. Among the carboxylic acids and salts which may be used in this invention are those having a carboxyl group joined directly to the hydrophobic group. The alkane sulfonic acids and salts include those having a sulfonic group directly linked to the hydrophobic groups, for example, those having no polar substituents, unsubstituted alkane sulfonic acids, and some having somewhat uncertain structural formulae, such as oxidation products of sulfurized olefins, sulfonated resins, etc.; and sulfonic groups joined through an intermediate linkage, such as an ester, amide, ether, or other miscellaneous linkages having, for example, two or more linkages. The alkyl aromatic sulfonic acids and salts that may be used in this invention include those wherein the hydrophobic group is joined directly to the sulfonated aromatic nucleus, such as alkyl benzenes, alkyl naphthalenes, alkyl phenols, aromatic condensates, alkyl aromatic ketones, etc.; and those having a hydrophobic group joined to the sulfonated

aromatic nucleus through an intermediate group, such as an ester, amide, or imide, ether, etc. Among the sulfuric esters, or so-called sulfates, which may be used as a surface-active agent in this invention, are those having a sulfate group joined directly to the hydrophobic group which contains no other polar structures or contains other polar structures, such as sulfonated oil; and those having a sulfate group joined through an intermediate linkage, such as an ester, an amide, or an ether linkage, etc.

Salts of the alkyl aromatic sulfonic acids have been found to be desirable as a surface-active agent for this invention. It is generally preferred to use the alkyl aromatic sulfonates that have a hydrophobic group joined directly to the sulfonated aromatic nucleus. For example, as illustrated in the following structural formula, "R" represents the hydrophobic portion of the molecule:

It has been found that the alkyl aryl sulfonates containing 8 to 20 carbon atoms in the "R" or hydrophobic portion of the molecule are generally preferred and those containing 12 to 15 carbon atoms in the hydrophobic portion of the molecule are especially preferred. The alkyl aryl and alkyl benzene sulfonates may contain more than one side chain or "R" group, although molecules containing only one side chain or "R" group are generally preferred. While the cation portion of the molecule may be composed of various alkali and alkali-earth metals, it generally is preferred to form the salts of these compounds with sodium or potassium. The molecular weight range of the anionic portion of the alkyl aryl sulfonates which may be used as a surface-active agent for this invention varies between about 275 and 450, with those having a molecular weight of about 300 to about 375 being generally preferred.

A mixture of surface-active agents may be used in the surface-active solution of the process of this invention, although it is generally preferred to employ only one agent at a time. The amount of surface-active agent per volume of oil being treated may vary considerably and, in part, depends upon the particular surface-active agent being used and also upon the amount of soap to be removed. For example, in the description of the appended sketch, 0.000042 pound of surface-active agent per gallon of oil satisfactorily removed the naphthenic soap from the oil. The maximum amount of surface-active agent depends upon the solubility of the agent in water. However, it is usually preferred to use about 0.3 pound per gallon of the surface-active agent to about as little as 0.00004 pound per gallon of water. When larger amounts of surface-active agent are used, foaming or emulsifying may occur. Of course, even smaller amounts of this agent may be used when the permitted maximum soap content is relatively high or when the oil to be treated contains a very small amount of soap. The weight per cent of the surface-active agents in an aqueous solution may vary between about 0.0005 to about 0.3 weight per cent with 0.001 to 0.1 being generally preferred.

While a continuous type of process is illustrated in the appended sketch for the soap removal step, a batch-type process is equally feasible.

The pressures employed in this process may vary over a wide range from subatmospheric to superatmospheric with a slight superatmospheric pressure being generally preferred. Because the viscosity of the oils being treated by the process of this invention may increase substantially on lowering the temperature, it is generally preferred to employ temperatures above about 100° F. in the soap-separating step.

The oils that may be treated by the process of this invention include the entire naphthenic crude oil or particular fractions of these crude oils. Since the naphthenic acids desired to be recovered are generally found in the kerosene, gas oil and light lubricating oil fractions, it is generally preferred to treat distillates boiling in this range or in temperature range of about 325° F. to about 800° F. It is particularly preferred to treat diesel fuel oils and burner oils boiling within the range of about 325° F. to about 725° F. as the soap content is very critical in these fuels.

In order to illustrate the process and results of this invention, the following examples are presented of the soap-removal step for the purpose of illustration, but are not, however, to be taken as limiting the scope of the invention.

The following examples, results of which are given in the table below, were conducted as follows:

In each of the experiments summarized in the following table, a 500 cc. sample of an alkali-treated, straight-run distillate from a California crude oil having an initial boiling point of 381° F. and an end point of 720° F. and a soap number of 0.0356, was mixed with an aqueous surface-active solution in a separatory funnel for five minutes and then allowed to stand for twenty minutes in order to obtain a phase separation. The aqueous phase was drawn off and the soap number of the treated oil was determined. In each of the tests, the surface-active agent was a sodium alkyl aryl sulfonate having an average molecular weight of about 350.

Summary of results

Test	Treatment	Soap No.
1	None	0.0356
2	50 cc. of 0.026 wt. percent of surface-active solution	0.005
3	100 cc. of 0.026 wt. percent of surface-active solution	0.004
4	150 cc. of 0.026 wt. percent of surface-active solution	0.002
5	200 cc. of 0.026 wt. percent of surface-active solution	Nil
6	50 cc. of 0.005 wt. percent of surface-active solution	0.007
7	100 cc. of 0.005 wt. percent of surface-active solution	0.005
8	150 cc. of 0.005 wt. percent of surface-active solution	0.003
9	250 cc. of 0.005 wt. percent of surface-active solution	0.001
10	50 cc. of 0.10 wt. percent of surface-active solution	0.001
11	100 cc. of 0.10 wt. percent of surface-active solution	Nil
12	150 cc. of 0.10 wt. percent of surface-active solution	Nil

As illustrated by Example 6 of the foregoing table, it can be seen that a very small amount

of surface-active agent removes substantially all of the soap from the oil.

I claim:

1. A process of producing diesel fuel oils and soaps of naphthenic acids from the naphthenic-acid-containing petroleum hydrocarbon fractions boiling within the range of about 325 to about 725° F. which comprises washing the hydrocarbon fractions with an aqueous caustic solution whereby the naphthenic acids are converted to the corresponding soap, settling the washed mixture and separating the resultant hydrocarbons and aqueous phase containing derived naphthenic soaps; washing the separated hydrocarbons with an aqueous solution consisting essentially of water and 0.001 to about 0.1 weight per cent of an alkyl aryl sulfonate having an average molecular weight of about 350 in a volume ratio of said hydrocarbons to said aqueous solution of about 1:1 to about 20:1; and settling the washed mixture and separating an aqueous phase containing naphthenic soaps and resultant naphthenic-soap free diesel fuel oil.

2. A process of producing fuel oils and soaps of naphthenic acids from naphthenic-acid-containing petroleum hydrocarbon fractions boiling within the range of about 325 to about 800° F. which comprises treating the hydrocarbon fractions with an aqueous alkali solution whereby the naphthenic acids are converted to the corresponding soaps, separating the treated hydrocarbon and aqueous alkali solution containing naphthenic soaps; treating the separated hydrocarbons with a dilute aqueous solution consisting essentially of water and a water-soluble, alkyl aromatic sulfonate; and separating an aqueous phase containing said naphthenic soaps from a resulting petroleum hydrocarbon phase.

3. A process of producing fuel oils and soaps of naphthenic acids from naphthenic-acid-containing petroleum hydrocarbon fractions boiling within the range of about 325 to about 800° F. which comprises treating the hydrocarbon fractions with an aqueous alkali solution whereby the naphthenic acids are converted to the corresponding soaps; separating the treated hydrocarbon and aqueous alkali solution containing naphthenic soaps; treating the separated hydrocarbons with a dilute aqueous solution consisting essentially of water and a water-soluble alkyl benzene sulfonate; and separating an aqueous phase containing said naphthenic soaps from a resulting petroleum hydrocarbon phase.

CYRIL R. TURNER.
